COMBINED STOOL AND TABLE

George B. Hansburg, New York, N. Y., assignor,
by mesne assignments, to Metropolis Bending
Company, Metropolis, Ill., a corporation of
Illinois

Application January 30, 1937, Serial No. 123,138

3 Claims. (Cl. 155—123)

This invention relates to a combined stool and table for infants.

An object of the present invention is the provision of a piece of furniture which may be used as an infant's stool and table and which is simple in construction, attractive in design, and inexpensive to manufacture.

Another object of this invention is the provision of a piece of furniture which may be used as an infant's stool and which at the same time comprises a table surface sufficiently large to support the infant's playthings, dishes, clothing or the like.

The above and other objects of the present invention may be realized through the provision of a combined infant's stool and table which comprises a table surface surrounding a seat for the infant which is preferably located in the center of the table surface. The seat is so located relatively to the table surface that the articles placed upon the table surface can be conveniently and easily reached by the seated child.

The invention will appear more clearly from the following detailed description when taken in connection with the accompanying drawings showing by way of example a preferred embodiment of the inventive idea.

In the drawings:—

Figure 1 is a section along the line 1—1 of Figure 3 and shows a combined infant's stool and table constructed in accordance with the principles of the present invention;

Figure 2 shows the combined infant's stool and table partly in front elevation and partly in section;

Figure 3 is a horizontal section along the line 3—3 of Figure 2;

Figure 4 is a perspective view of the device;

Figure 5 is a section through a combined infant's stool and table of a somewhat different form;

Figure 6 is a section along the lines 6—6 of Figure 5;

Figure 7 is a partial sectional view along the line 7—7 of Figure 5, on a somewhat larger scale;

Figure 8 is similar to Figure 7 and shows the device with the back plank in the closed position;

Figure 9 shows the outline of the fabric constituting the infant's seat shown in Figures 5 and 6;

Figure 10 shows a foot support of a somewhat different form.

The combined infant's stool and table shown in Figures 1 to 4 of the drawings comprises a flat table surface 5 of a horizontal plank 6 which

may be rectangular in form, and which is provided with a central opening 7. A rectangular outer frame 8 supports the plank 6 and is firmly connected therewith.

Four legs 9, 10, 11 and 12 are hinged at 13 to the outer frame 8 and are also connected with the frame 8 by means of pairs of links 14. Due to this arrangement, the table is made collapsible so that its legs 9 to 12 may be folded and placed within the frame 8 when the article is not being used.

The central opening 7 of the horizontal plank 6 is preferably substantially rectangular in form and is provided with rounded edges 15. A rectangular inner frame 16 surrounds the opening 15 and is connected by bolts 17 with the plank 6.

The inner frame 16 serves as a support for the infant's seat which is preferably made of fabric and has the form of a bag 18 provided with two openings 19 and 20 for the infant's legs. The feet of the infant may be supported by a plank 35 made of wood, cardboard or the like and situated within a pocket 36 which is attached by flaps 37 and 38 to the seat 18.

As shown in Figure 3, the seat 18 is suspended from the frame 16 upon several pins or bolts 21. The upper portion of the seat 18 is provided with a corresponding number of grommets 22, the positions of which correspond to those of the supporting bolts 21 and which are slipped over the bolts 21 when the seat 18 is attached to the device. Any number of cushions 23 and 24 may be placed, if desired, upon the seat 18.

The combined infant's stool and table may be provided with a canopy comprising two parallel supports 25 and 26, the lower portions of which are provided with slots 27 and 28, respectively. Thumb screws 29 and 30 extend through the slots 27 and 28 and are firmly screwed into the outer frame 8. The supports 25 and 26 may be swung relatively to the seat 18 and may be held by the thumb screws 29 and 30 in any desired inclined position.

A preferably rectangular canopy frame 31 carries the canopy fabric 32 and is pivotally connected with the supports 25 and 26 by means of thumb screws 33 and 34. Due to this arrangement, the canopy frame 31 carrying the fabric 32 may be tilted at any desired angle relatively to the supports 25 and 26. The distance of the canopy fabric 32 from the table surface 5 may be conveniently adjusted due to the provision of the slots 27 and 28.

As shown in Figure 4, the canopy supports 26 and 27 may be conveniently folded, thereby facili-

tating the carrying of the device. Obviously, the canopy and its supports 26 and 27 may be removed, if the combined stool and table are to be used indoors.

5 Figures 5 to 9 illustrate parts of a piece of furniture which comprise a horizontal plank 40 having a flat table surface 41 and provided with a central opening 42. A rectangular inner frame 43 surrounds the opening 42 and is connected 10 by any suitable means with the lower surface of the plank 40.

15 The frame 43 is used as a support for the infant's seat which has the form of a bag made of fabric and comprises a seat portion 44, a back portion 45, two side portions 46 and 47, a front portion 48 adapted to pass between the legs of the infant and a foot rest portion 49 terminating in a pocket 50. The upper portion of the frame 43 is provided with recesses, so that slots 51 are 20 formed between the lower surface of the plank 40 and the upper surfaces of the frame 43. The upper ends of the seat portions 45 to 48 extend through the slots 51 and have the form of pockets 52. Dowels 53 are situated in the pockets 52 and 25 are used for holding the seat portions in their respective positions.

30 The feet of the infant are supported by a plank 54 made of wood, cardboard or the like which is inserted into the pocket 50. The plank 54 is held in place by two metallic side pieces or brackets 55 and 56 (Figs. 5 and 6) which are pivotally connected at 57 and 58, with two supports 59 and 60 so that the blank support can swing 35 around the pivots 57 and 58. The upper ends of the supports 59 and 60 are suspended from pivots 61 and 62, respectively, which are carried by the frame 43.

40 A U-shaped rod 63 is used for adjusting the position of the foot support. The intermediate lower portion 64 of the rod 63 passes through openings formed in the lower ends of the supports 59 and 60. The upper bent ends 65 of the U-shaped rod 63 may be inserted into several 45 openings 66 provided in the frame 43, thereby adjusting the position of the foot support depending upon the height of the infant.

50 A plank 67 carrying a cushion 68 is used to support the back of the infant and constitutes a closure for the opening 42 when the device is not being used. The plank 67 is connected by snap fasteners 69 with the seat portion 44 and carries fasteners 80 used for holding the plank 67 in the closed position.

55 The foot support shown in Figure 10 comprises a plank 70 situated in a pocket 71 of a bag 72 constituting the infant's seat. The plank 70 is inserted into the pocket 71 and may be glued thereto, or it may be secured by any other suit-

able means. The plank 70 is supported by metallic angular side pieces or brackets 73, only one of which is shown in the drawings. The side pieces 73 are provided with horizontal flanges upon which the plank 70 rests. The upper end of 5 each side piece 73 carries a bolt 74 passing through a slot 75 provided in a vertical support 76, which is similar to the support 60 shown in Figure 5. The position of the foot support may be adjusted by winged nuts 77 carried by the 10 bolts 74. The construction is otherwise substantially similar to that shown in Figures 5 to 9.

15 As is apparent from the foregoing description, one of the characteristic features of the present invention is the provision of an infant's seat 20 which is surrounded by or conveniently combined with a substantially large table surface capable of serving as a support for the infant's playthings, his dishes or his garments, and preventing the infant from dropping his playthings or 25 other objects on the floor. The device may be used outdoors, since the adjustable canopy will prevent exposure of the infant to the sun, and since the construction of the seat is such that it is impossible for the infant to lift himself out 30 of the seat.

35 Of course, the described constructions may be modified in various particulars or be applied in many varied relations without departing from the spirit and scope of the invention as claimed, 40 the practical embodiments herein illustrated merely showing some of the various features of the invention.

What is claimed is:

1. In combination, a table, an opening in the 35 table top thereof, a bag type seat suspended by said table beneath said opening and a substantially rigid back rest extending from the bottom of said seat upwardly through said opening, and detachably connected to said seat. 40

2. In combination, a table, an opening in the 45 table top thereof, a bag type seat suspended by said table beneath said opening and a substantially rigid back rest extending from the bottom of said seat upwardly through said opening, said back rest being removably secured to said seat and of a size to close said opening. 50

3. In combination, a table, an opening in the 55 table top thereof, a bag type seat suspended by said table beneath said opening and a substantially rigid back rest extending from the bottom of said seat upwardly through said opening, said back rest being removably secured to said seat and of a size to close said opening, and means for supporting said back rest in position to close said opening and complete the table surface.

GEORGE B. HANSBURG.
